US00D625004S

(12) **United States Design Patent**
McGrady et al.

(10) **Patent No.:** **US D625,004 S**
(45) **Date of Patent:** **** Oct. 5, 2010**

(54) **LUER**

(75) Inventors: **Nicholas McGrady**, North Wales, PA (US); **Kenneth J. Chesnin**, Philadelphia, PA (US)

(73) Assignee: **Medical Components, Inc.**, Hatleysville, PA (US)

(**) Term: **14 Years**

(21) Appl. No.: **29/342,823**

(22) Filed: **Sep. 1, 2009**

(51) **LOC (9) Cl.** **24-02**

(52) **U.S. Cl.** **D24/129**

(58) **Field of Classification Search** D8/330-348; D24/129-130, 112; 604/533, 905, 523, 535, 604/539, 249, 403; 264/150

See application file for complete search history.

(57) **CLAIM**

The ornamental design for a luer, as shown and described.

DESCRIPTION

FIG. 1 is an isometric view from beyond the proximal end of a luer according to the present invention.

FIG. 2 is an isometric view from beyond the distal end of a luer according to the present invention.

FIG. 3 is a right side view of the luer shown in FIG. 1; the left side view is a mirror image thereof.

FIG. 4 is a top view of the luer shown in FIG. 1; the bottom view is a mirror image thereof.

FIG. 5 is a distal end view of the luer shown in FIG. 1; the details within the center opening are shown in dashed lines and form no part of the present invention; and,

FIG. 6 is a proximal end view of the luer shown in FIG. 1; the details within the center opening are shown in dashed lines and form no part of the present invention.
